UNITED STATES PATENT OFFICE.

DUANE H. CHURCH, OF NEWTON, MASSACHUSETTS.

WATCH-HAND.

SPECIFICATION forming part of Letters Patent No. 605,269, dated June 7, 1898.

Application filed December 17, 1895. Serial No. 572,392. (No model.)

To all whom it may concern:

Be it known that I, DUANE H. CHURCH, of Newton, in the county of Middlesex and State of Massachusetts, have invented certain new and useful Improvements in Watch-Hands and Supporting Mechanism Therefor, of which the following is a specification.

This invention relates to the attachment of watch-hands to the cannon-pinion and hour-wheel of a watch-movement; and it has for its object to provide simple and efficient means for securing the hands in such manner that they can be applied and removed without liability of injury to any of the delicate parts of the watch-movement and when in place will be held positively without liability of either hand projecting into the path of the other.

To these ends the invention consists in the improvements which I will now proceed to describe and claim.

Of the accompanying drawings, forming a part of this specification, Figure 1 represents a side view of a center-staff, showing in section thereon the cannon-pinion, hour-wheel, and hands. Fig. 2 represents a section on line 2 2 of Fig. 1. Fig. 3 represents a side view of the minute-hand. Fig. 4 represents an edge view of the socket of the hour-hand. The same letters of reference indicate the same parts in all the figures.

In the drawings, a represents the cannon-pinion proper, and a' the hub or sleeve portion thereof, having bearings a^2 a^3 for the hour-wheel h . Between said bearings the portion a' is provided with longitudinal slots a^{13} , between which are left longitudinal sections a^4 . These sections are curved inwardly and present curved bearings to the center-staff b . The center-staff is provided with a peripheral recess along that portion which coincides with the sections a^4 , said recess presenting a gradual back taper from its deepest portion to a point near the outer end of the staff.

Although I have thus particularly described the construction of the cannon-pinion and its engagement with the center-staff, I do not wish to be understood as limiting myself thereto, as the cannon-pinion and center-staff

may be constructed in any other suitable manner to effect a suitable engagement between the two.

The cannon-pinion is extended outwardly beyond the outer end of the center-staff and provided with an internal screw-thread, said thread surrounding a chamber or socket at the outer end of the center-staff. The minute-hand m is secured to the cannon-pinion by a screw i , formed to engage the internal thread in the extension of the cannon-pinion. Said screw is preferably secured permanently to the minute-hand and may be either made integral therewith or in a separate piece, staked or otherwise secured in a socket formed in the minute-hand. By thus attaching the minute-hand to the cannon-pinion I do away with the pressure required in forcing the minute-hand to place on its bearing on the cannon-pinion when the minute-hand has a socket pressed into frictional engagement with the cannon-pinion, as heretofore, such pressure being liable to injure the jewel on which the inner end of the center-staff has its bearing. I also insure the firm seating of the minute-hand upon the outer end of the cannon-pinion, so that the position of the minute-hand is positively assured and its liability of being deflected so as to enter the path of the hour-hand is prevented. The screw connection between the minute-hand and the cannon-pinion also enables the minute-hand to be removed simply by the use of a screw-driver, no special tool being required and no liability incurred of cracking the dial by the prying operation usually required in removing the minute-hand.

My improvements further include as a means for securing the hour-hand o a back-tapered seat o' on the hub of the hour-wheel, said seat surrounding the outer portion of the cannon-pinion, and an elastic back-tapered socket o^2 , formed on the hour-hand, said socket being transversely cut at o^3 and made of elastic construction, so that it embraces and closely fits the seat o' . The back taper of the seat o' and socket o^2 is such that when the socket is sprung onto said seat it cannot be accidentally removed, the effect of the natural contraction of the socket on the back-tapered

seat being to press the socket downwardly against the shoulder ^{or} ³⁰, which limits its downward movement. Hence the hour-hand may be said to be automatically seated or pressed downwardly and held out of the path of the minute-hand. The elastic socket enables the hour-hand to be readily turned on the hub of the hour-wheel in adjusting its position, the socket being readily enlarged by forcing a screw-driver into its slot or opening, the resulting contraction insuring the proper bearing of the hour-hand against the shoulder, so that there is no liability of lateral displacement of the hour-hand as a result of its adjustment.

I claim—

The combination with a center-staff, of a cannon-pinion having its hub extended outwardly beyond the center-staff and provided with an internal screw-thread, and a minute-hand having a screw formed to engage said thread.

In testimony whereof I have signed my name to this specification, in the presence of two subscribing witnesses, this 13th day of ²⁵ December, A. D. 1895.

DUANE H. CHURCH.
